UNITED STATES PATENT OFFICE.

WILLIAM R. WIDDUP, OF SPARTANBURG, SOUTH CAROLINA, ASSIGNOR TO DRAPER COMPANY, OF HOPEDALE, MASSACHUSETTS, A CORPORATION OF MAINE.

THREAD-CUTTING TEMPLE FOR LOOMS.

1,203,828.

Specification of Letters Patent.

Patented Nov. 7, 1916.

Application filed August 21, 1915. Serial No. 46,645.

To all whom it may concern:

Be it known that I, WILLIAM R. WIDDUP, a citizen of the United States, and resident of Spartanburg, county of Spartanburg, 5 State of South Carolina, have invented an Improvement in Thread-Cutting Temples for Looms, of which the following description, in connection with the accompanying drawing, is a specification, like characters 10 on the drawing representing like parts.

This invention relates to thread cutting temples for looms and the principal objects thereof are to provide means to more certainly sever the thread upon the first forward movement of the lay after transfer and also to sever the thread more closely to the selvage or edge of the web of cloth.

The loom temple forming part of the present invention is of the type forming the subject matter of Patent No. 585,465 granted June 29, 1897 in which the temple-head is provided with means to cut the filling end extending from the selvage of the cloth to the automatic filling replenishing mechanism after the latter has been operated to supply the shuttle with fresh filling. The temple-head disclosed in the patent aforesaid is slotted transversely at its outer end to receive coöperating fixed and movable 20 blades which are arranged to engage and cut the filling end. These blades comprise a single stationary blade fixed to the temple-head and an oscillating and sliding movable cutter, the end of which is hook shaped and 25 is bifurcated to receive and to coöperate with both sides of the stationary blade. Looms employing this type of thread cutter are usually provided with filling parting and holding devices which sever the end of the 30 filling leading to the carrier upon replenishment at the same time grasping the filling and carrying the end laterally so that it is brought into the field of action of the temple thread cutter where it is again severed 35 in proximity to the selvage. In the prior devices the stationary blade lies intermediate of the blades of the movable cutter. In my improved device another stationary blade is located closely adjacent to the end of the 40 temple roller so that one side of the blade acts as a guide for the selvage while the edge of the other side of said blade forms a cutter, thus the thread is severed closely 45 to the selvage thus making a neater cut of the cloth and also preventing the possibility of 50

the severed end being whipped into the fell of the cloth by the suction of the shuttle as it passes across the loom.

In temple thread cutters of the usual construction above described the wear of the 60 parts due to the constant vibration of the lay in time renders the coöperation of the blades ineffective so that the cutter will not operate properly upon the first beating up of the lay after transfer, the cutters instead of 65 severing the end merely grasping the same so that the subsequent movement of the temple serves to place a tension upon the thread which will cause it to break between the temple thread cutter and the holding device thereby leaving a loose end which is 70 likely to be whipped into the loom, thus damaging the appearance of the goods. By providing a plurality of stationary cutters, adapted to coöperate with a corresponding 75 number of movable cutting blades the severance of the end of the filling is assured, first, because the cutters are steadied in their movement by increased lateral bearing surfaces and second by reason of the fact that a 80 larger number of cutting blades engage the thread.

The nature and objects of the invention will more fully appear from the following description and the accompanying drawings 85 and will be pointed out in the annexed claims.

The drawings illustrate a temple thread cutter of the type shown in Patent No. 585,465 aforesaid in which my improvement has been embodied.

Figure 1 is an end elevation of the outer end of the temple-head. Fig. 2 is a front elevation of the temple, and Fig. 3 is a detail view of a group of stationary blades. 95

The temple may be of the usual construction comprising a head 1 having a rearwardly extending arm or slide bar 2 adapted to be supported in the usual stand upon the breast beam of the loom. The temple 100 head comprises the pod 3 and cap 4 which are secured together by a screw 6 provided with a locking nut 7 in the usual manner a toothed roll 8 being mounted upon a shaft 9 journaled in brackets in the ends of the 105 cap.

Adjacent the outer end of the roller the pod is preferably provided with a vertical slot 10 in which is seated a plurality or group of stationary cutting blades 11 which 110

desirably are separated by a plate or shim 12 corresponding in thickness to the thickness of the movable cutter blade, one of these blades being located adjacent to the edge of 5 the toothed roller 8 and forming a guide for the selvage of the cloth. The blades and shim may conveniently be clamped in position by a screw 13 in the usual manner.

While I have illustrated in the drawing 10 two stationary blades coöperating with corresponding movable cutting blades it will be understood that a greater number of stationary blades and a correspondingly greater number of movable blades may be utilized 15 within the spirit and scope of my invention.

The movable cutter 14 may be of the general form illustrated in Patent No. 585,465 aforesaid which comprises a body portion 14 slidably mounted in a slot 15 in the cap, the 20 rear end of the blade 15 resting upon a portion of the base of the pod upon which it is adapted to have rocking and sliding movement. The forward end of the cutter may be bifurcated but preferably is provided 25 with a plurality of attached steel blades 16. These blades are hook shaped as in the construction disclosed in the patent above referred to. The rear end of the cutter is provided with a downwardly extending heel 17 30 having a laterally extending stud 18, and a spring 19 connected to the stud 18 and a stud 20 upon the slide bar 2 serves to maintain the cutter normally in extended position. The temple is provided with the usual heel 35 21 adapted to be engaged by the lay as it beats up the filling.

In operation the cutter stands normally 40 with its hooked end or cutters 16 in elevated position and removed a distance from the front of the blades 11. As the lay comes forward at each beat, after the filling has been thrown into the shed, the lay first strikes the heel 17 of the cutter, causing the hooked end to move first downwardly so as 45 to engage any filling which may have been brought into the field of the temple thread cutter by the cutting and holding devices which operate at transfer. Upon every movement of the lay the cutters 16 are with- 50 drawn into coöperative relation with the stationary blades 11 thus severing the filling end. By reason of the fact that an added stationary blade 11 is closely adjacent to the end of the temple roll the severance of 55 the thread will take place at a point as near the selvage as is possible, and by reason of

the fact that there are a plurality of stationary blades coöperating with a plurality of movable blades the severance of the filling upon the first beat up of the lay is assured 60 so that not only a neater web of cloth is produced but the likelihood of a broken end of filling being drawn into the web of cloth by reason of the improper operation of cutters is avoided. 65

It is of course understood that this operation of the temple thread cutter occurs just prior to the time the lay engages the heel 21 of the temple and just before the regular running filling thread is beaten in so that 70 the temple thread cutter cannot catch the thread but is always in position to sever upon the first pick after transfer, the filling end which extends from the selvage to the filling holder. 75

It is to be understood that this invention is not limited to the particular construction herein shown but may be applied to any other suitable form of loom temple.

Having thus described my invention what 80 I claim as new and desire to secure by Letters Patent is:

1. A temple-head provided with a toothed roll and having a plurality of stationary blades one of which lies closely adjacent to 85 the end of said temple roll, and forms a guide for the edge of the selvage of the cloth, a coöperating movable cutter having a plurality of cutter blades alternating with said stationary blades and means for actuating said movable cutter whereby certain of the movable blades will pass between said stationary blades in coöperation with the adjacent edges of the successive stationary blades. 95

2. A temple-head provided with a toothed roll and having a transverse slot at its outer end, a plurality of stationary cutters fixedly secured in said slot, one of said cutters being closely adjacent to the end of said toothed 100 roll, and forming a guide for the edge of the selvage of the cloth, an oscillating and reciprocating cutter having a plurality of hooked blades disposed in alternating relation to said stationary blades, the edges of 105 said movable blades coöperating with adjacent edges of said stationary blades and means for actuating said movable cutter.

In testimony whereof, I have signed my name to this specification.

WILLIAM R. WIDDUP.
